MERCURY-VAPOR APPARATUS.

1,188,578.

Specification of Letters Patent. Patented June 27, 1916.

Original application filed November 24, 1911, Serial No. 662,131. Divided and this application filed November 28, 1913. Serial No. 803,421.

To all whom it may concern:

Be it known that I, Percy H. Thomas, a citizen of the United States, and resident of Upper Montclair, county of Essex, State of New Jersey, have invented certain new and useful Improvements in Mercury-Vapor Apparatus, of which the following is a specification.

My invention relates to mercury vapor apparatus such as may be found useful for a production of light, of ultra violet rays, or for other useful agencies. In some instances, however, my invention may be applied to other media than mercury.

It has been shown by Peter Cooper Hewitt, and others, for example in a number of patents issued to Hewitt, that current continuous in direction and at low voltage can be made to traverse an exhausted container having suitable electrodes therein, provided means are applied for overcoming the natural reluctance to starting existing in such apparatus. In a device of this character there is a loss of voltage and development of heat at each of the electrodes, the voltage loss being approximately constant, and further there is a vaporization or dissipation of conducting material at the surface of the cathode. There is also a loss of voltage suffered by the current in traversing the space between the electrodes which loss of voltage depends very particularly upon the dimensions and disposition of the exhausted space, the character of the gas or vapor therein and the pressure or density thereof. Furthermore in the operation of such a system, it is usually advantageous to use a liquid cathode and mercury has been found a suitable material.

During the operation of such a device, in view of the heat generated, the temperature of a solid electrode will rise until, by radiation and by convection from the vapor coming in contact therewith, the rate dissipation of heat equals the rate of generation thereof. In the case of a liquid electrode, however, the generation of heat will tend to raise the temperature of the electrode but this will automatically cause an evaporation from the liquid since the liquid is

in a closed space and the vapor pressure therein must be that of the saturation pressure of the vapor at the temperature of the liquid. On the other hand if there is any point on the container to which the vapor has access which is cooler than the electrode at its surface, the saturation pressure of the vapor at this point will be less and a portion of the vapor will be condensed until the pressure at this point be appropriate to the saturation pressure at the lower temperature. This produces a difference in the pressure between the vapor near the liquid electrode and the pressure at the cool point of the container, causing a flow of vapor and the evaporation of additional vapor from the liquid electrode in proportion to the amount withdrawn. Thus there will be a continuous evaporation and condensation of the vapor from the liquid electrode at the cool spot in the container so long as the difference in temperature is maintained. This process will proceed very rapidly unless there be physical obstruction in the path of the moving vapor, thus impeding its progress and causing a permanent difference in the pressure between the two points in the container.

In a certain form of practical lamp of the type described by Hewitt, above referred to, the apparatus is so proportioned as to keep the pressure of the vapor relatively low, thus permitting a relative small loss of voltage in the tube and a wide distribution of the current flow. This condition can be secured only by maintaining the mercury cathode at or near a certain definite temperature which will ordinarily be confined in the general neighborhood of the boiling point of water. In some other forms of lamp a higher pressure of the mercury vapor, where mercury is the material used, is desirable. This is obtained by using a different proportion of parts, or a higher current, so that the temperature of the electrode will be higher than in the former type. In this class of apparatus the pressure of the mercury vapor is sufficiently high to confine the flow of current between the electrodes to a relatively narrow space,

usually to a space much smaller than the diameter of the container. In this case it is found that the temperature in the path traversed by the current may be very high. 5 With such devices the containers have frequently been made of quartz, in a re-vitrified more or less transparent form, with the resultant advantage that higher temperatures can be attained than could be conveniently secured with ordinary glass. 10 However, it may be noted that as the current path becomes hot, as a result of the increased pressure or density within the container that it becomes feasible to maintain 15 the surface of the tube much cooler than the temperature of the vapor in the current path, since the current path no longer touches the wall of the container.

One of the features of my invention includes the forming of a container in such a lamp out of commercial glass of a composition resembling that found suitable for a lower pressure type of lamp. I secure this result by disposing the necessary cooling 25 surface largely near the current path, thus permitting a relatively large diameter of container and a relatively wide separation in location between the current path and the glass wall. I find that while the current 30 may flow near the surface of the glass, at or near the electrodes, that the temperature of the glass is maintained within a reasonable limit nevertheless; perhaps by a dispersing of heat along the glass wall to the neighboring electrode. 35

My invention contemplates means for controlling the distribution of mercury or other liquid in a vapor electric device so that a permanent apportioning of the mercury between the various points or the confining of the mercury at a predetermined point may be secured with the object of preventing the formation of drops of liquid which might fall upon a hot portion of the container and 45 cause a momentary excessive pressure of vapor or other irregularities which appear to occur sometimes in various forms of vapor electric apparatus, in the absence of protective means.

50 I will describe the invention more particularly in the form set forth in the accompanying drawings in which—

Figures 1 and 2 represent a lamp adapted for relatively high pressure operation.

55 In Fig. 1, I have shown a container, 1, which, if desired, may be made of glass of relatively high melting point or which may be made of vitrified quartz or like material, if desired. This container is shorter than 60 the ordinary form of vapor lamps adapted to operate at low pressure on account of the high voltage per inch in length resulting from the higher operating temperature of the cathode. I show at each end electrode 65 pockets 2 and 3 supplied with conducting

material which constitute the electrodes, here shown as mercury; lead-in wires of the usual form are shown at 4 and 5. I provide a throat 6 in immediate proximity to the electrode 3. This throat, being narrowly restricted, will become heated producing a spot of high temperature at the point 7. If the level of the material of the electrode 3 is relatively low the cooling surface of this electrode is sufficient to cause a condensation thereon with a consequent filling up of the electrode chamber. However, as the level of the electrode material reaches the highly heated point 7, there is a tendency for more rapid evaporation of the electrode material which produces a balance between heat generated and heat dissipated and maintains the electrode in equilibrium. In this device the bulb 8 acts as a condensing chamber for the lamp. 70 75 80

85 In Fig. 2 I show a tube somewhat similar to Fig. 1, having a condensing chamber vertically over the electrode 3. The electrode 3 has a relatively small surface exposed to the vapor at 9 with the result that the current path at this point has little opportunity to flicker. The same arrangement as here shown in connection with the electrode 3, the condensing chamber 8 and the throat 10 may be utilized for both electrodes if desired. I 90 have indicated the general location of the current path by the dotted lines marked 11. 95

100 While I have shown particular embodiments of my invention in the drawings of this application, I do not wish to limit myself to these particular forms, for my invention is broad enough to cover any structures which bring about the same results as those attained herein by substantially equivalent means or arrangements. Neither do I limit myself to any one particular vapor pressure, for any desired pressure may be utilized within the practical limits of the apparatus, determined either by the matter of temperature, light density, efficiency, temperature 105 or other conditions. 110

115 This application is a division of my application Serial Number 662,131, filed November 24th, 1911.

I claim as my invention:

1. Means for regulating the distribution of electrode material in a mercury vapor tube, said mercury vapor tube including a mercury electrode, means for replenishing the liquid in said electrode, said means having a capacity somewhat in excess of the natural rate of diminution of the electrode and additional means capable of causing a local development of heat, said last named means being located at the normal operating level of the electrode whereby any tendency to the raising of the level of the electrode is arrested by the more rapid evaporation of the electrode material as the level of the additional local heating means is reached. 120 125 130

2. A vapor tube for a vapor electric apparatus comprising a container exhausted to a high degree of vacuum, electrodes therein of liquid material, an electrode pocket therefor at one end of said tube provided with a leading-in wire, means for cooling said electrode and a narrow constriction in the end of said tube at or near the normal level of the electrode material in the said electrode pocket, whereby a highly heated portion of said con-

striction contacts with any excess electrode material above the normal level.

Signed at New York in the county of New York and State of New York this 24th day of November A. D. 1927
